UNITED STATES PATENT OFFICE.

CHESTER A. CHANCELLOR, LOREN G. McMANNAMA, AND CARLEY E. HOUGHTON, OF MINDENMINES, MISSOURI.

ENGINE TRIP FOR STEAM SHOVELS.

Application filed February 14, 1921. Serial No. 444,751.

To all whom it may concern:

Be it known that we, CHESTER A. CHANCELLOR, LOREN G. McMANNAMA, and CARLEY E. HOUGHTON, citizens of the United States, 5 residing at Mindenmines, in the county of Barton and State of Missouri, have invented new and useful Improvements in Engine Trips for Steam Shovels, of which the following is a specification.

10 This invention relates to steam shovels or excavators and has for its object the provision of means operated by certain movement of the dipper stick whereby to release the latch which holds the hinged bottom of 15 the dipper or scoop.

An important object is the provision of mechanism of this character which is entirely automatic in action so as to avoid any necessity for the employment of a craneman and 20 which will therefore economize on labor.

Another object is the provision of mechanism of this character which will operate automatically when the dipper stick is run out or extended to its maximum extent and 25 which will also automatically operate when the dipper stick is retracted or run in slightly when the dipper stick is in a certain angular position with respect to the ground, this latter mentioned feature being essential 30 inasmuch as it obviates risk of inadvertently dumping the scoop or dipper during loading.

Another object is the provision of a device 35 of this character which may be added as an attachment to ordinary existing excavating devices of this type without involving any alterations therein, the entire tripping mechanism being merely attachable.

An additional object is the provision of 40 a device of this character in which the control of the dumping dipper is positive, which possesses the advantage of being simple and inexpensive in construction and installation, highly efficient in use, durable in 45 service, and a general improvement in the art.

With the above and other objects and advantages in view, the invention consists in the details of construction to be hereinafter 50 more fully described and claimed and illustrated in the accompanying drawings in which—

Figure 1 is a side elevation of a portion of a steam shovel having our device applied thereto end showing it in loading position,

Figure 2 is a plan view, the boom being omitted,

Figure 3 is a side elevation showing the parts in position ready to dump,

Figure 4 is a view similar to Figure 3 60 showing the trip means,

Figure 5 is a fragmentary side elevation showing a different position of the latch pawl,

Figure 6 is a similar view showing another position of the latching pawl, and

Figure 7 is a cross sectional view on the line 7—7 of Figure 3.

Referring more particularly to the drawings, the letter A designates the end portion 70 of the supporting boom of a steam shovel of ordinary type, B designates the dipper stick carrying the usual rack C engaged by a pinion D, E designates the guide plate, F designates the pulley carried by the boom, 75 G designates the hoisting cable trained over the pulley, and H designates the dipper or scoop connected by a sheave I with the cable G and having the usual hinged bottom J held in place by a sliding keeper or latch 80 K. Ordinarily a rope or the like is connected with the latch K for releasing the hinged bottom of the dipper or scoop when it is desired to dump the latter.

In carrying out the invention we provide 85 a bar 10 mounted for longitudinal movement above and in spaced relation to the dipper stick B and this bar is formed with a series of spaced transverse notches 11. One end of this bar is pivotally connected by a 90 slot and pin connection 12 with a lever 13 pivoted intermediate its ends, as shown at 14, near the free end of the dipper stick. The lower end of this lever 13 has connected 95 therewith a flexible member such as a chain 15 which is in turn connected with the latch K of the dipper. The other end of the bar 10 is pivotally connected with a lever 16 which is pivoted intermediate its ends upon 100 a stud or post 17 rising from the dipper stick. The other end of the lever 16 is connected with a plunger rod 18 slidable through the arms of a U-shaped bracket 19. Secured on this plunger rod is a collar 20 engaging against one end of a coil spring 21 105 which encircles the plunger rod and abuts at its other end against the outermost arm of the U-shaped bracket. The function of the spring 21 is to hold the bar 10 normally in such position that the lever 13 will extend at 110

right angles to the dipper stick B so as not to pull upon the chain 15. This is the normal position of the parts when the bottom J of the dipper is closed and the parts are intended to remain in this position while the dipper or scoop goes through the necessary movement to effect loading thereof.

Secured upon the guide E is a hollow housing 22 preferably cylindrical in shape and having its upper end 23 closed and formed in one side with a vertical slot 24. Located within this housing is a plunger cup 25 which carries a laterally extending stem 26 upon which is pivoted a depending pawl 27 of the shape shown. This particular shape of the pawl is for the purpose of throwing its center of gravity to one side of the axis of the housing for a purpose to be hereinafter described. Engaging within the cup 25 is a coil spring 28 which engages an adjusting cup member 29 within the upper portion of the housing, the member 29 being in turn engaged by an adjusting screw 30 threaded through the closed top of the housing. The purpose of this spring 29 is to permit vertical movement of the cup member 25 and consequently the pawl 27 under certain conditions, as will be explained.

In the operation of the device it will be seen that under normal conditions with the dipper stick inclined downwardly, as shown in Figure 1, the tripping mechanism above described is entirely inactive. When the dipper or scoop has been lowered and it is desired to dump the same, the dipper stick is of course elevated to the proper position, after which the usual engine driven means is operated to run the dipper stick out or extend it over the wagon or other vehicle to receive the load. When the dipper stick is run out to the end of its movement the plunger 18 will engage against the guide E whereupon the lever 16 will be rocked upon its pivot 17 which will result in longitudinal movement of the bar 10 toward the dipper and this will of course result in swinging the lever 13 upon its pivot 14 into the position shown in Figure 4, whereupon the lower end of the lever 13 will exert a pull upon the chain 15 and cause retraction of the latch K so that the hinged bottom of the dipper will swing downwardly to release the load.

It is, however, possible to dump the dipper without running out the dipper stick to its maximum extent. This, however, cannot be accomplished until the dipper stick has been elevated to a predetermined angle with respect to the horizontal, this angle being determined by the specific construction and consequent center of gravity of the pawl 27. When this angle has been determined and the parts correspondingly adjusted, it will be seen that when the dipper stick is swung to the proper angular position, the pawl 27

will bear upon the top of the bar 10. When the dipper stick B is run out part way, or as far as desired except to its maximum extent, there will be no action on the part of the pawl 27 as the notched bar 10 will ride idly beneath its end. When it is desired to dump the dipper it is merely necessary that the dipper stick moving mechanism be reversed to retract the dipper stick a few inches whereupon one of the notches 11 will engage the heel of the pawl 27 and hold the member 10 stationary. Subsequent retraction of the dipper stick will then of course result in moving the lever 13 rearwardly and this will of course pull upon the chain 15 and release the latch K.

When it is subsequently desired to retract the dipper stick still more so as to prepare for the next loading operation, continued retraction of the dipper stick will result in swinging the pawl 27 into the position shown in Figure 6 and then into the position shown in Figure 5, the slot 24 and spring 28 permitting the necessary vertical movement of the pawl. When the dipper stick B is then run out the pawl will be moved from the position shown in Figure 5 to the position shown in Figure 6 and then to the position shown in Figure 1 without in any way affecting the bar 10. As long as the dipper stick B is inclined downwardly, as for example as shown in Figure 1, the pawl 27 will be out of engagement with the bar 10 so that the dipper stick may be run in and out freely without any danger whatever of operating the trip.

From the foregoing description and a study of the drawings it will be apparent that we have thus provided a simply constructed and consequently inexpensive trip attachment for steam shovels or excavators which is very easy to install, which requires no alterations in the structure of the steam shovel itself and which will operate very efficiently, especially as the trip is positively power actuated.

While we have shown and described the preferred embodiment of our invention, it is of course to be understood that we reserve the right to make such changes in the form, construction, and arrangement of parts as will not depart from the spirit of the invention or the scope of the subjoined claims.

Having thus described our invention, we claim:

1. In a steam shovel, the combination of a boom, a dipper and dipper stick, a guide on said boom for the dipper stick, a dipper door on the dipper provided with a latch, longitudinally movable bar carried by the dipper stick, and an operative connection between the forward end of said bar and the retaining latch of the dipper door, and means connected with the other end of the bar and engageable with the guide upon the out-

ward movement of the dipper stick to its maximum extent whereby to move the bar to release said latch.

2. In a steam shovel including a boom, a dipper stick, a stationary guide on the boom, a dipper and a dipper door having a latch; a trip mechanism comprising a longitudinally movable bar carried by the dipper stick, an operative connection between the 10 forward end of said bar and the retaining latch of the dipper door, and means connected with the other end of the bar and engageable with the guide upon the outward movement of the dipper stick to its maximum extent whereby to move the bar to release said latch.

3. In a steam shovel including a boom, a dipper stick, a stationary guide on the boom, a dipper and a dipper door having a latch; a trip mechanism comprising a longitudinally movable bar carried by the dipper stick, an operative connection between the forward end of said bar and the retaining latch of the dipper door, and means connected with the other end of the bar and engageable with the guide upon the outward movement of the dipper stick to its maximum extent whereby to move the bar to release said latch, said means comprising a pivoted lever 25 connected with the second mentioned end of said bar at one end and carrying a spring pressed plunger at its other end engageable with the guide.

4. In a steam shovel including a boom, a dipper stick, a stationary guide on the boom, a dipper and a dipper door having a latch; a trip mechanism comprising a longitudinally movable bar carried by the dipper stick, an operative connection between the 30 forward end of said bar and the retaining latch of the dipper door, and means connected with the other end of the bar and engageable with the guide upon the outward movement of the dipper stick to its maximum extent whereby to move the bar to release said latch, said means comprising a lever pivoted intermediate its ends upon the dipper stick and connected at one end with the second mentioned end of said bar, a 35 bracket carried by the dipper stick, a plunger carried by the other end of said lever and slideable through said bracket and a spring urging said plunger toward the guide to hold the bar in inactive position.

5. In a steam shovel including a boom, a dipper stick, a dipper carried by the stick and having a door, a latch device normally holding said door closed, and a guide stationary upon the boom, a trip mechanism comprising a lever pivoted intermediate its 50 end upon the forward end of the dipper stick, a flexible member connected with the lower end of said lever and with the latch of the dipper door, a bar disposed above and in spaced relation to the dipper stick and 55 connected with the other end of said lever, a lever pivoted intermediate its ends upon the other end portion of the dipper stick and pivotally connected at one end with the other end of said bar, and a spring pressed 60 plunger carried by the other end of said second named lever and engageable with the guide upon the outward movement of the dipper stick to its maximum extent 65 whereby to move the bar to swing said first 70 named lever.

6. In a steam shovel structure including a boom, a dipper stick, a dipper carried by the stick and having a door, a latch device normally holding the door closed, and a stationary guide upon the boom, a trip mechanism comprising a lever pivoted intermediate its 75 ends upon the forward end of the dipper stick, a flexible member connected with the lower end of said lever and with the latch 80 of the dipper door, a bar disposed above and in spaced parallel relation to the dipper stick and connected with the other end of said lever, a lever pivoted intermediate its 85 ends upon the other end portion of the dipper stick and pivotally connected at one end with the other end of said bar, a spring pressed plunger carried by the other end of said second named lever and engageable with the guide upon the outward movement of the 90 dipper stick to its maximum extent whereby 95 to move the bar to swing said first named lever, a member secured upon the guide, and a vertically movable downwardly spring pressed swingable pawl carried by said last 100 named member and engageable with said bar, the bar being formed with notches engageable with the end of the pawl.

In testimony whereof we, affix our signatures.

CHESTER A. CHANCELLOR.
LOREN G. McMANNAMA.
CARLEY E. HOUGHTON.
